UNITED STATES PATENT OFFICE.

JOHN R. HAMILTON, OF YONKERS, NEW YORK, ASSIGNOR TO AUTOMATIC SPRINKLER COMPANY OF AMERICA, OF NEW YORK, N. Y., A CORPORATION OF NEW YORK.

DESIGN FOR A SPRINKLER-HEAD OR SIMILAR ARTICLE.

55,124.

Specification for Design.

Patented May 11, 1920.

Application filed July 22, 1919. Serial No. 312,579. Term of patent 14 years.

To all whom it may concern:

Be it known that I, JOHN R. HAMILTON, a citizen of the United States, residing in Yonkers, county of Westchester, State of New York, have invented a new, original, and ornamental Design for a Sprinkler-Head or Similar Article, of which the following is a specification, reference being had to the accompanying drawing, which forms a part of the same, and in which—

Figure 1 is a front view of a sprinkler head, showing my new design,

Fig. 2 is a perspective view thereof,

Fig. 3 is a detailed section showing part of the same taken substantially along the line 3—3 of Fig. 1; and

Fig. 4 is a partial section taken substantially along the line 4—4 of Fig. 2.

What I claim is:

The ornamental design for a sprinkler head or similar article, substantially as shown.

July 19th, 1919.

JOHN R. HAMILTON.
